UNITED STATES PATENT OFFICE.

JULIUS G. PEGEL, OF THOMPSONVILLE, CONNECTICUT, ASSIGNOR TO THE BIGELOW-HARTFORD CARPET CO., OF THOMPSONVILLE, CONNECTICUT, A CORPORATION OF MASSACHUSETTS.

DESIGN FOR A CARPET OR RUG.

48,606.

Specification for Design.

Patented Feb. 22, 1916.

Application filed December 21, 1915. Serial No. 68,094. Term of patent 3½ years.

To all whom it may concern:

Be it known that I, JULIUS G. PEGEL, a citizen of the United States, residing in Thompsonville, in the county of Hartford and State of Connecticut, have invented a new, original, and ornamental Design for a Carpet or Rug, of which the following is a specification, reference being had to the accompanying drawing, forming part thereof.

The figure is a face view of approximately a quarter section of a carpet or rug showing my new design.

I claim:

The ornamental design for a carpet or rug as shown.

JULIUS G. PEGEL.

Witnesses:

W.M. J. MULLIGAN,
JAS. L. FOLSOM.
